MEANS TO SUSPEND SHOWER BATH CURTAINS

Filed Oct. 22, 1928

JACK JOSEPH MOSS, INVENTOR
BY *Eduard Neufeld*, ATTORNEY

UNITED STATES PATENT OFFICE.

JACK JOSEPH MOSS, OF MOUNT VERNON, NEW YORK, ASSIGNOR TO I. B. KLEINERT RUBBER COMPANY, OF NEW YORK, N. Y.

MEANS TO SUSPEND SHOWER-BATH CURTAINS.

Application filed October 22, 1928. Serial No. 314,212.

My invention relates to improvements in the means used to suspend rubber shower bath curtains from overhanging rods or poles and has reference particularly to the specific arrangement of the upper end of the curtain itself as well as to the improved features of the hooks which support the curtain.

The invention has for its object to provide an improved hook construction of the character described which is efficient in application and use and which may be readily detachable from the curtain being suspended.

A further object of my invention is to afford the upper end of a rubber bath curtain with suitable pockets to receive and detachably carry my improved curtain hook.

A still further object of this invention is to provide the upper end of a rubber bath curtain with a pocket construction formed by affixing certain sections of the rubber material to the body of the curtain proper by means of a rubber cement and without the use of stitching or other methods ordinarily applied.

I accomplish these objects by means of the construction and combination of parts hereinafter described, set forth in the appended claims, and illustratively exemplified in the accompanying drawings, in which Figure 1 is an elevational view of the inner side of a shower bath curtain showing the arrangement of the upper end of the latter and the improved hook for slidably supporting the curtain from a rod or pole; Figure 2 is a substantially transverse sectional view of the same taken on lines 2—2 of Figure 1; Figure 3 is a longitudinal sectional view taken on lines 3—3 of Figure 2 and showing portions of the curtain broken away; and Figure 4 is an elevational view of the back of the upper end of a curtain constructed in accordance with the present invention.

Referring to the drawings, 10 denotes a curtain preferably of rubber or rubberized fabric having its upright sides turned over on the back and attached thereto by means of an adhesive cement. The upper end of the curtain is likewise turned over on the back and attached at spaced intervals to the curtain by cement. The hem 11 thus formed

at the upper end of the curtain is preferably a deep hem so as to provide sufficient material above the pole 12 to conceal it from the outside.

Suspension is usually afforded a curtain of this character at spaced intervals of say four or five inches and in the present invention similar spacing is allowed between points of suspension. The space inside the hem 11 becomes one large pocket to which access is had through openings 13 between the body of the curtain material and the lower end of the turned down end of the material forming the hem 11. These openings 13 are established by not applying cement to the sections when the hem is being made. Figure 4 illustrates the manner in which the material adjacent each opening is re-enforced and a guideway arranged to receive the hook members hereinafter described. 14 designates patches or pieces of the material cut, for example, in quadrants each having two sides at right angles to each other, one side being disposed along a line 75 above and parallel to the lower end of the hem 11 and the other side being disposed perpendicular to the hem line, intersecting it at the outside dimension of the opening 13. The pieces 14 are arranged in pairs, the perpendicular sides of the two pieces forming the sides of adjacent openings 13. Each piece 14 is fixed to the underlying material throughout its entire surface by means of cement.

The curtain just described is hung from a pole 12 by means of hooks 15 each of which in the present instance comprises a strip of metal bent to form a downwardly directed hook 16 and upright back portion 17 which is bent parallel to the back portion of the hook 16 and spaced slightly from the latter, as illustrated in Figure 2. The upper free end of the back portion 17 is bent to form an eye 18 on its side toward the hook 16. In 95 the eye 18 is mounted the mid portion of a spring 19 having outwardly and downwardly projecting arms 20. The arms 20 at these lower ends project substantially beyond the sides of the material of the hook 100 and are capable of being sprung towards each other. The ends of the arms 20 are

further bent towards each other and parallel to the mid portion projecting through the eye 18.

To assemble the hooks 15 in the curtain, 5 the upper end of the back portion 17 in each case is inserted into the opening 13, the arms 20 coming into contact with the upright sides of pieces 14 and ends of the opening 13, and being yieldable they spring towards each 10 other until the back portion 17 has been inserted far enough to bring the ends of the arms 20 past the lower end of the hem. At this point the arms, being free, spring outwardly again into the pocket and prevent 15 the hook from being withdrawn without contracting the arms again.

In hanging position the lower end of the hem 11 rests on the loop of the hook between the back portion 17 and parallel portion of 20 the hook proper 15, and due to the position of the patches 14 at each side of the hem the latter at its lower end is re-enforced to a considerable extent.

It will be understood of course that 25 various changes may be made in the shape of the hook and the application of the re-enforcing elements without departing from the spirit of the invention, as claimed.

Having now described my invention and 30 the manner in which the same may be used, what I claim and desire to secure by Letters Patent is:

1. A curtain supporting device, comprising 35 a curved portion to encircle a pole or rod and an upright back portion to be inserted into the hem of the curtain through an opening of a width corresponding to the width of the device, and a spring anchor for the upper end of said back portion having 40 arms normally projecting beyond the width of the back portion and capable of being

pressed towards each other to project through the opening in the hem of the curtain.

2. A curtain to be supported from supporting devices, comprising a hem portion formed at its upper end, said hem being provided with spaced openings along its lower edge, and patches attached to the curtain and overlapping the hem and adjacent portion of the curtain at the opposite ends of the said openings. 45 50

3. A curtain supporting device, comprising a strip of metal curved at one end to encircle a pole or rod, an upright straight mid-portion and an upright back portion bent from the lower end of the mid-portion, and a triangular spring catch attached to the upper end of the back portion at one of its angles, the other angles being normally 60 projected beyond the sides of the curved and straight portions of the device and capable of being depressed towards each other substantially as described. 55 60

4. The combination of a curtain provided with a hem along its upper end having a plurality of spaced openings, a series of supporting devices for said openings, each device comprising a curved end to encircle a pole, upright straight intermediate and 70 back portions, said back portion being insertable into an opening in the hem, and a spring catch carried by the upper end of the back portion to be contracted to permit the back to project through the opening and 75 normally extended beyond the ends of the opening to prevent the removal of the back portion from the hem. 70 75

In testimony whereof he has affixed his signature.

JACK JOSEPH MOSS.
